(57) **CLAIM**

The ornamental design for a camera backpack, as shown and described.

DESCRIPTION

FIG. 1 is a front, right, top perspective view of a camera backpack, showing our new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 2;

FIG. 10 is an enlarged view of detail 10 in FIG. 2;

FIG. 11 is an enlarged view of detail 11 in FIG. 3;

FIG. 12 is an enlarged view of detail 12 in FIG. 4;

FIG. 13 is an enlarged view of detail 13 in FIG. 5;

FIG. 14 is an enlarged view of detail 14 in FIG. 5;

FIG. 15 is an enlarged view of detail 15 in FIG. 7;

FIG. 16 is an enlarged view of detail 16 in FIG. 7;

FIG. 17 is an enlarged view of detail 17 in FIG. 7;

FIG. 18 is an enlarged view of detail 18 in FIG. 7;

FIG. 19 is an enlarged view of detail 19 in FIG. 7;

FIG. 20 is an enlarged view of detail 20 in FIG. 8; and,

FIG. 21 is an enlarged view of detail 21 in FIG. 8.

The dashed broken lines in the figures are for the purposes of illustrating portions of the camera backpack and form no part of the claimed design.

The short-short-long dashed broken lines immediately adjacent to the claimed areas in the views represent the boundaries of the design and form no part of the claimed design. The dash-dot-dash broken lines are for notating enlarged views and form no part of the claimed design.

1 Claim, 15 Drawing Sheets
